Primary Examiner — Prabhakar G Deshmukh*(74) Attorney, Agent, or Firm* — Hasse & Nesbitt LLC; Daniel F. Nesbitt(57) **CLAIM**

The ornamental design for a spiral unlock tool, as shown and described.

DESCRIPTION

FIG. 1 is a perspective view of a spiral unlock tool showing my new design;

FIG. 2 is a front elevational view thereof, the rear elevational view being a mirror image thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front elevational view of an alternate embodiment of FIG. 2; and,

FIG. 8 is a front elevational view of another alternate embodiment of FIG. 2.
